UNITED STATES PATENT OFFICE.

GEORGE E. LLOYD, OF CHICAGO, ILLINOIS.

BLACK-LEADING MACHINE.

SPECIFICATION forming part of Letters Patent No. 298,595, dated May 13, 1884.

Application filed July 12, 1883. (No model.)

To all whom it may concern:

Be it known that I, GEORGE E. LLOYD, of Chicago, in the county of Cook and State of Illinois, have invented certain new and useful 5 Improvements in Black-Leading Machines; and I do hereby declare that the following is a full, clear, and exact description of the invention, which will enable others skilled in the art to which it appertains to make and use 10 the same, reference being had to the accompanying drawings, and to letters of reference marked thereon, which form a part of this specification.

The object of my invention is to furnish a 15 new, economical, and thorough machine for distributing what is commonly known as "black lead"—*i. e.*, powdered plumbago—over the matrix from which an electrotype is to be taken—in other words, performing the 20 process which in electrotyping is known as "metallizing." This I accomplish by a rapidly-vibrating brush, which distributes the black lead over and in the irregularities and interstices of a matrix, said matrix being placed 25 on a bed, which is slowly reciprocated under the said brush, the whole process being performed in an air-tight box, and being actuated through the medium of the new and simple mechanism hereinafter described in the specification, and illustrated in the drawings, in which—

Figure 1 is a side elevation of my machine. Fig. 2 is a plan view of the same. Figs. 3 and 4 and 6 are detail views, and Fig. 5 shows the 35 mechanism for reciprocating the bed-plate.

In the drawings, A represents the frame of my machine, which is of a rectangular shape, and rests on four legs. Depending from the side frame, about the center of length of the 40 same, are the hangers *aa*—one on either side—in the lower ends of which the drive-shaft C is journaled. On one end of the shaft is the drive-pulley C', which is connected by a belt to a fast-and-loose pulley, and on the other 45 end of the said drive-shaft is a small pulley C, which indirectly, as will hereinafter be explained, communicates motion to the bed-plate. The drive-shaft is provided near either end, just within the hangers *aa*, and almost, if not 50 immediately, under the side frames, with the eccentrics *bb*. These eccentrics *bb* are made

simply by making that part of the shaft eccentric—*i. e.*, by a displacement of the center of the same about one-third the diameter of the said shaft. Journaled on these eccentrics are 55 the connecting-rods *cc*, the other end of which is pivoted to a stud projecting from a sleeve, D. This sleeve surrounds the threaded lower ends of the vertically-reciprocating rods E, which, passing upward through suitable guides 60 in the side frame, are secured to the back of the brush F. The lower threaded ends of the reciprocating rods are provided with the nuts *d*—one above and one below the sleeve D—thus, as will readily be perceived, making the 65 rods and brush affixed thereto adjustable vertically.

The brush F crosses the machine from side to side, and is made, preferably, of camel's hair. The back of it is secured to the top ends of 70 the vertically-reciprocating rods E, which may be bent inward, flattened, and perforated to receive screws or other means for securing said brush.

Reciprocating longitudinally under the 75 brush F, on suitable ways or ledges, *ee*, projecting inward from the side frames, is the bed-plate G, the means for operating which I will now describe.

In the side frame adjacent to the pulley C', 80 near the end of the machine, I make a circular hole, and insert in the same the sleeve *h* of the pinion *h*, which latter is prevented from revolving by screws or bolts passing through 85 it into the side frame.

Journaled in the bore of the pinion *h* and its sleeve *h* is a shaft, H, which has on its inner end a sprocket-wheel, *i*, and on its outer end the loose pulley I. This pulley I is connected by a belt to the small pulley on the end of the 90 drive-shaft. Between the loose pulley I and the pinion *h* is a pinion, J, fast on the shaft H, and projecting from an arm of the said pulley I is a stud, on which are journaled two small connected pinions, *l* and *m*, which mesh with 95 the pinions *h* and *J*, respectively. The pinion *h* has, say, thirty cogs, and the pinion *J* thirty-one, and the pitch of the cogs of these two pinions are relatively different; but concerning the pinions *l* and *m*, while their pitch 100 may be different, the number of cogs in each is the same. Thus it will be observed that with

every revolution of the pulley I the pinion J will be urged forward one cog, (or the difference between the number of cogs on it and the stationary pinion h ,) which motion it communicates to the shaft H. This mechanism is adopted to materially decrease the speed of the shaft H without the necessity of expensive gearing.

About midway the length of the machine, 10 on the inside of the side frame, adjacent to the sprocket-wheel i, fast on the inner end of the shaft H, is a corresponding sprocket-wheel, m', journaled on a stud projecting horizontally from the contiguous frame. These sprockets 15 i and m' are connected by a suitable link-chain, n, and their distance apart corresponds to the length of the bed-plate G. From one of the links of this chain n there is projecting laterally a stud, n', on which is pivoted a connecting-rod, o, the other end of which is pivoted to a lug, g, projecting downward from the under surface of the said bed-plate. When motion is imparted to the endless chain n by the sprocket i, a given point thereon, starting 20 from said sprocket, will move forward to and around sprocket m', then back again to and around sprocket i, describing a reciprocal motion, the forward and return strokes of which are on different horizontal planes separated the diameter of the sprockets. Now, if 25 we consider the aforesaid "given point," (the stud n',) it will be apparent that through the medium of the connecting-rod o it will impart a reciprocal motion to the bed-plate G.

30 In operation the matrix is placed on the bed-plate G and a suitable quantity of black lead sprinkled over the same. The machine is then set in operation, the bed-plate carrying said matrix back and forth under the vibrating brush as many times as is deemed necessary to thoroughly distribute the particles of black-lead in all the interstices and depressions of said matrix, whereupon the machine 35 is stopped and said matrix removed.

It will thus be observed from the foregoing 45 description that my machine is cheap and of simple construction, but thorough in the accomplishment of its object.

If desired, instead of the chain m, a belt may be used; nor do I deem it beyond the scope of 50 my invention if other means than the connecting-rod be adopted to impart the motion of the chain to the bed-plate.

What I claim as new, and desire to secure by Letters Patent, is—

1. The combination of the brush, the vertically-reciprocating rods, the lower ends of which are threaded, with the sleeve placed thereon, having a laterally-projecting stud, two nuts placed, respectively, above and below said sleeve, the connecting-rods pivoted to said stud, and eccentrics actuating said connecting-rods.

2. The combination of the bed-plate, the link-chain, and the means described for reducing the speed of the drive-shaft, consisting of shaft H, pinion h, and sleeve h', pinion J, pulley I, and pinions l and m, substantially as set forth.

3. In a black-leading machine, the vibrating 70 brush and means for operating the same, consisting of the drive-shaft, eccentrics thereon, and connecting rods or links, in combination with the reciprocating bed-plate and means for operating the same, consisting of the endless chain and pitman, and devices, as described, for reducing the speed of the drive-shaft and imparting the same to said endless chain, substantially as set forth.

In testimony that I claim the foregoing as 80 my own I hereunto affix my signature in presence of two witnesses.

GEORGE E. LLOYD.
